Charles G. Gilbert of Leeds, Maine
Letters Patent

The subject referred to in these Letters Patent and making part of the same containing a description in the words of the said Charles G. Gilbert himself of his improvement in the Horse Power.

I call to whom these presents shall come, the witness that I Charles G. Gilbert of Leeds, in the County of Penobscot, in the State of Maine have invented a new and useful improvement in Horse Power, of having Machine to combine all the advantages of those Powers jointly and at a much less expense rendering it acceptable to most of Farmers. I do hereby declare that the following is a full and exact description thereof. The general construction and mode in which the Horse travels is similar to that of Pitts, the Horse travelling upon an endless chain, 14' A. 2' A. 4' frame of the machine, a side bar, B. endless chain on which the Horse is to travel, C. D. wheels over which the said chain is to pass E. E. E. E. wheels or friction rollers which is to support the chain directly under the Horse, E. F. wheels of cast iron over which the chain is to run and kept from falling so low as it otherwise would, G. a wheel where the power is taken from G. and over which a band is placed to carry other machinery. What I claim as my own invention and not previously known in the above described machine is as follows.

1st First. The peculiar construction of the endless chain, the left wheel fasten the links or cups fixed to the chain having heads which in turn are to contain as says. 2nd Second. The wheel G. over which the chain is to pass is to have holes on its periphery at such distances and sizes as will be proper for receiving the pegs formed in the chain when put in motion. 3rd Third. To have two sets of rollers over which the chain is to pass as is shown by the above drawing I represent the wheel in which the Horse travels

34.

and 3. The rollers which support the chains which will make less friction than the usual mode of having one set of rollers, and then extending the whole (nearly) width of the chain. Although I now use leather as the band to my chains I propose to use iron if found by experience to be best. I therefore claim the principle or manner herein set forth whether the same be made precisely as herein described or in any other, which is substantially the same, producing a similar effect by analogous means.
